UNITED STATES PATENT OFFICE.

WALLACE H. WITHERINGTON AND HARRY A. SHANKLIN, OF TOLEDO, IOWA.

DESIGN FOR A CABINET.

SPECIFICATION forming part of Design No. 33,178, dated September 4, 1900.

Application filed July 20, 1900. Serial No. 24,343. Term of patent 14 years.

To all whom it may concern:

Be it known that we, WALLACE H. WITHERINGTON and HARRY A. SHANKLIN, citizens of the United States, residing at Toledo, in the county of Tama and State of Iowa, have invented and produced a new and original Design for a Cabinet, of which the following is a specification, reference being had to the accompanying drawing, forming part thereof.

o The drawing shows the entire desk and cabinet in perspective.

As shown in the drawing, the leading or material features of our design consist of a flat top 10, having at one side of its front a panel 11, extending from the top to the floor and having the remainder of its front open. At one side of the desk is a panel 12, extending from a point out to the vertical center of its side to the back of the desk and to the floor and having a space in the same side from the said panel to the front edge of the desk. In this space is an ornamental bracket 13, ex-

tending from the top of the desk to the side of said panel. At one corner of the desk is the square leg 14. From the inner edge of the front panel 11 is a vertical partition 15 to project rearwardly and extend over the top of the desk to the floor, and from the front edge of the panel 12 is a vertical partition 16 to project laterally to meet the partition 15 and to extend from the top of the desk to the floor, the back and remaining side of the desk being perfectly smooth.

Having thus described our invention, what we claim as new, and desire to secure by Letters Patent of the United States, is—

A design for a cabinet, substantially as herein shown and described.

WALLACE H. WITHERINGTON.
HARRY A. SHANKLIN.
